REFRIGERATING APPARATUS

Edmund F. Schweller, Dayton, Ohio, assignor to
General Motors Corporation, Dayton, Ohio, a
corporation of Delaware

Original application November 26, 1932, Serial No.
644,473. Divided and this application Septem-
ber 25, 1935, Serial No. 42,084

10 Claims. (Cl. 20—35)

The present invention relates to refrigerating apparatus and particularly to the construction of a door for a refrigerator cabinet and this application is a division of my co-pending application, Serial No. 644,473, filed Nov. 26, 1932.

5 Heretofore doors employed for closing the access opening of refrigerator cabinets have been built with a heavy framework to which was fastened an inner metal panel and on the outside of which was fastened an outer metal panel. Between the panels and framework there has been provided insulation, such as cork, which has been sealed by dipping in or covering it with hot asphalt to prevent the ingress of moisture thereto. Such doors have not been entirely satisfactory in that they are objectionably heavy, that they require a large amount of labor and that they are relatively expensive to produce.

10 An object of my invention is to provide a door for a refrigerator cabinet with improved insulating material therein.

Another object of my invention is to provide an improved door for a refrigerator cabinet in which the metal outer walls or panels form the main structural strength or framework of the door, so as to permit as light in weight construction as possible.

Further objects and advantages of the present invention will be apparent from the following description, reference being had to the accompanying drawings, wherein a preferred form of the present invention is clearly shown.

In the drawings:

Fig. 1 is a front elevational view of a refrigerator cabinet having a door constructed in accordance with the present invention secured thereto;

Fig. 2 is a fragmentary transverse sectional view taken on the line 2—2 of Fig. 1 showing the construction of the door of the present invention;

40 Fig. 3 is a view similar to Fig. 2 of a modified form of the door;

Fig. 4 is a fragmentary section of a further modification of the door; and

Fig. 5 is a section along the line 5—5 of Fig. 4 with the rubber member shown in Fig. 4 omitted.

In order to illustrate the present invention, I have shown in Fig. 1 of the drawings a refrigerator cabinet 10 which may be constructed as fully described in my co-pending application above referred to. The cabinet 10 comprises a plurality of insulated walls 11 surrounding a food storage compartment provided in the cabinet. A door 12 of general rectangular form serves as a closure member for an opening which provides

access to the refrigerated food compartment in cabinet 10.

The refrigerator cabinet door 12 comprises a relatively deep, rectangular, pan-shaped, sheet metal member 15 (see Fig. 2) which forms the back panel thereof and has flanged edges 16 which are fastened to wooden connecting strips 17 by suitable wood screws 18. The front of door 12 is formed by a flat sheet metal member 19 which has its edges 21 curled over the outer edges of the connecting strips 17, but spaced and insulated from the edges 16 of the rear panel 15. The connecting strips 17 are fastened by means of the machine screws 22 to bracket member 23 which is preferably spot welded to the sheet metal member 19. At the rear of the connecting strip 17, there is provided a rubber air seal 24 which is adapted to engage and seal against the outer surface of cabinet 10 about the door opening thereof. The rubber air seal 24 extends around the periphery of door 12 and has a forked end portion with one of the forks 25 fastened beneath the flange 16 of the pan member 14, while the other fork 26 extends over and covers the flanged portion 16 of the pan member 15 and thereby covers the wood screws 18. It will be understood that four such strips 17 are employed in the construction of the door 12 and that these strips are separate from one another and independently assembled in the door. In order to properly insulate the door 12, I provide an insulating panel generally represented by the reference character 28 therein. This insulating panel 28 is preferably placed in the door 12 after the strips 17 have been secured to the brackets 23 and prior to placing pan member 15 in position. The panel 28 is made of a plurality of rectangular frames 31 which are preferably of some light in weight and low heat conducting material such as wood. These frames 31 have sheets of bright, metallic foil 32 stretched thereon and fastened thereto by any suitable adhesive substance. After the foil 32 is applied to the frames 31, these frames are stacked and fastened together to provide the insulating panel 28 of predetermined thickness. Thus the sheets of bright, metallic foil 32 are held in spaced apart relation relative to one another to provide air spaces 34 between them. On each of the outer sides of the panel 28, there is provided a sheet of water proof paper 35 which is adapted to bear against the inner surface of the metal pans 15 and 19 after assembly of the door 12 has been completed. After the wood strips 17 have been secured to the brackets 23 on panel 19 to form a

rigid structure about the flanged edges 21 thereof and after having positioned the insulating panel 28 in position intermediate the spaced apart strips 17, the pan-shaped member 15 is then 5 assembled over the structure. The forks 25 and 26 of the gasket or air seal 24 are slipped over the edge 16 of the member 15 and member 15 is thereafter secured to the strip 17 by the wood screws 18 to complete the structure. Any suitable or desirable latch and hinges may be secured to the door 12 for providing a pivotal 10 mounting of the door 12 on cabinet 10. By this type of door construction a light weight insulating barrier of considerable thickness is placed 15 between the outer metal panels thereof.

In Figs. 3 to 5 inclusive of the drawings, a modified form of door construction generally represented by the reference character 40 is shown for the cabinet disclosed in Fig. 1. In this modified construction 40, a deep, metal, pan-shaped member 41 is provided with a flanged edge portion 42. An insulating panel generally represented by the numeral 43 is made up of a plurality of substantially rectangularly shaped frames 44 having sheets of bright metallic foil 45 therebetween. The insulating panel 43 is placed between the deep pan 41 and the front metal member 47 of door 40. A thick rubber member 51 is provided between the flanged edge 42 of the pan-shaped member 41 and the recessed attaching portion 49 of the outer sheet metal member 47. This rubber member 51 extends entirely around the door and is provided with an integral air sealing portion 53 which extends therefrom and rests 35 against the curled edge portion 48 of the outer member 47. The attaching portion 49 of member 47 is recessed sufficiently to accommodate the thick rubber member 51. This rubber member 51 thus acts as an insulation between the pan-shaped member 41 and the outer metal member 47 of the door 40.

In order to fasten the members 41, 47 and 51 together, with the insulating panel 43 between the metal members 41 and 47, I provide brass screws 45 which extend through the flanged edge portions 42 of the pan-shaped member 41 and are threaded into a tapped extruded portion 56 provided upon the recessed fastening portion 49 of the outer member 47. In order to cover the brass screws 55, the rubber member 51 is made in a sort of forked design so that a lip or extension 58 of rubber provided thereon extends over the heads of the brass screws and flanged edge 42 of the pan-shaped member 41. It will be seen that the modified door construction 40 comprises a minimum of elements which are namely, the insulating panel 43, the pan-shaped member 41, the outer sheet metal member 47 and the rubber member 51. This greatly simplifies the construction of doors and lowers the cost of doors by providing a very thick and light weight insulation between walls of the doors. The provision of the rubber member 51 between the pan-shaped member 41 and the outer metal member 47 prevents 65 the conduction of heat from the exterior of the door to the interior thereof by the metal walls. The screws 55 and the connecting portion thereof in contact with member 47 is so small that heat leak through the screws is negligible.

70 It is possible to entirely eliminate heat leakage by conduction through screws 55 and I have shown in Figs. 4 and 5 of the drawings, an arrangement for accomplishing this feature of the invention. In the construction shown in Figs. 4 and 5 slots 61, of substantially key-hole form,

are cut in the recessed attaching portion 49 of the outer metal member 47. Within the smaller portion 62 of slot 61 (see Fig. 5) there are slidably inserted nuts 63 formed of a material having low heat conducting properties such as hard rubber or fiber each of which is provided with a squared groove 64 upon its periphery for engaging the edges of the narrow portion 62 of slot 61 so that the nuts 63 will be tightly held against rotation during the act of turning the screws 55 thereinto. The construction shown in Figs. 4 and 5 is otherwise similar to that shown in Fig. 3 and it is obvious that the insulating nuts 63 prevent transference of heat from the one metal member 47 to the other metal member 41 of the door 40 through screws 55.

From the foregoing, it will be seen that I have provided improved door constructions for closing an access opening provided in a refrigerator cabinet. My improved doors are light in weight, thus eliminating wear of the hinges employed pivotally mounting the door on a cabinet and thereby preventing sagging of the door. My invention provides doors that are highly efficient for insulating the interior of a cabinet from atmosphere exterior thereof.

While the forms of embodiments of the invention as herein disclosed, constitute preferred forms, it is to be understood that other forms might be adopted, all coming within the scope of the claims which follow.

What is claimed is as follows:

1. A refrigerator door construction including an outer sheet metal member having a curled-in edge, said edge portion being curled 180° and having a fastening portion extending inwardly therefrom, a thick rubber gasket member mounted upon the fastening portion, said fastening portion being recessed with respect to the curled portion to form a ledge to accommodate the thick gasket member, a deep pan-shaped inner sheet metal member having a flanged edge, insulation between the inner and outer sheet metal members, the flanged edge of the inner sheet metal member resting against the thick rubber gasket member and being insulated from the outer sheet metal member by the thick gasket member, and fastening means for fastening the flanged edge of the inner member to the fastening portion of the outer member.

2. A refrigerator door construction including a sheet metal facing member, a second sheet metal facing member, insulation between said facing members, one of said facing members having an edge curled inwardly of the periphery thereof and a fastening portion extending from the curled-in edge, the other of said facing members having a flanged edge lying along and adapted to be secured to the fastening portion of said one of said facing members, an insulating strip interposed between the fastening portion of said one of said members and the flanged edge of the other of said members, and means for securing the fastening portion of said one of said members to the flanged edge of the other of said members with the insulating strip therebetween.

3. A refrigerator door construction including a sheet metal facing member, a second sheet metal facing member, insulation between said facing members, one of said facing members having an edge curled inwardly of the periphery thereof and a fastening portion extending from the curled-in edge, the other of said facing members having a flanged edge lying along and adapted to be secured to the fastening portion

one facing member and adapted to engage a wall of an opening to be closed by said door.

10. A refrigerator door construction including a sheet metal facing member, a second sheet metal facing member, insulation between said facing members, one of said facing members having an edge curled inwardly of the periphery thereof and a fastening portion extending from the curled-in edge, the other of said facing members having a flanged edge lying along and adapted to be secured to the fastening portion of said one of said facing members, said fastening portion being recessed with respect to the curled-in portion of said one of said members and forming a ledge for receiving an insulating strip, a molded rubber strip interposed between the recessed fas-

tening portion of said one of said members and the flanged edge of the other of said members, and means for securing the fastening portion of said one of said members to the flanged edge of the other of said members with the molded rubber strip therebetween, said molded rubber strip having an integral hollow resilient gasket seal portion extending over the curled-in edge of said one facing member and adapted to engage a wall of an opening to be closed by said door, said molded rubber strip also having an integral flexible lip portion fitting over the flanged edge of said other facing member and concealing said securing means.

EDMUND F. SCHWELLER.
